[57] CLAIM

The ornamental design for an animal confinement barn, as shown and described.

DESCRIPTION

FIG. 1 is a fragmentary perspective view taken from the top, one side and one end of an animal confinement barn showing my new design with portions broken away to aid in illustration, the opposite end being the same as the end shown;

FIG. 2 is a top plan view thereof;

FIG. 3 is a bottom plan view thereof;

FIG. 4 is a side elevational view thereof, the opposite side being the same as the side shown.

The center of the barn is broken away in FIGS. 2, 3 and 4 to indicate indeterminate length.
